ELECTRON MICROSCOPE VACUUM SYSTEM

Friedrich Krause, Berlin, Germany

Application May 13, 1940, Serial No. 334,965
In Germany May 8, 1939

4 Claims. (Cl. 250—141)

The present invention relates to electron microscopes and more particularly pertains to means for maintaining different pressures therein.

It is essential for satisfactory sharp depicting and high resolving of the images in an electron microscope that the course of the electrons in the apparatus be not influenced in addition to the diffraction in the object or the deflection in the coils. It is known that electrons are influenced by layers of air similarly to light rays by opal glass.

It is therefore of importance to produce a very high vacuum below 10^{-3} millimeters of mercury in the electron microscope. This applies more particularly to points which are of essential importance for the formation of images as, for instance, directly below the object, at the lenses and at similar points.

However, it may be necessary to employ higher pressure at certain points of the apparatus. The use of cold cathodes as light ray source of an electron microscope may be indicated as an example. Pressures of about 10^{-2} millimeters of mercury are necessary in this case but such pressures in the depicting space of the electron microscope gives rise to blurred images. Moreover, the presence of gas particles at other points of the apparatus may be of great importance. For example, it is frequently necessary when examining organic substances such as cellular films and the like to employ a lower vacuum of about 10^{-1} to 10^{-2} millimeters of mercury as is otherwise necessary for a sharp depicting possibility in the electron microscope. In the case of very high vacuum (below 10^{-3} millimeters of mercury) the dried brittle organic films are charged with electron rays during the examination. This may cause a distortion of the electron image by space charges and lead to a rupture of the films. The secondary heat produced during the passage of the electrons through the material can not be carried away which eventually leads to combustion. For this reason, it is advisable to carry away a large number of air particles at such points in the electron microscope where charging or heating is to be avoided. This may be effected by admitting air at these points through an air inlet valve.

In order to prevent the electron images from being affected by the aforesaid conditions or circumstances, there are provided according to the invention separate pump connecting pipes at the important image points which provide for a continuous suction of the residual gases or of the

cooling gases employed. The arrangement of separate pump connecting pipes at various points enables varying vacuum to be provided in the electron microscope at individual points according to requirement. Such important image points are situated for instance just below the anode diaphragm and in the vicinity of the lenses. The pipes may be connected separately to a separate pump or several pipes may be connected to a common pumping plant.

A constructional form of the invention is shown by way of example in the accompanying drawing. The electron microscope *a* is provided with a cold cathode *b* for voltages of about 80 kilo-volts and subjected to a pressure of about 10^{-2} millimeters of mercury. An air inlet valve (not shown) is arranged adjacent the cathode of the electron microscope. In order that the vacuum of 10^{-2} millimeters of mercury, which is not suitable for a sharp depicting of the image, may not pass into the lower part of the electron microscope, a throttle diaphragm *d* is provided in such a manner that it divides the high vacuum space of the electron microscope into an upper space belonging to the discharge tube and into a lower space belonging to the object and the lenses. A pump connecting pipe *e'*, connected to a pumping plant (not shown) is provided just below the anode diaphragm *c*.

Separate pump connecting pipes are provided at other important image points, in this case just below the lenses a pipe *e²* is provided below the objective lens *f* and a pipe *e³* is arranged below the projection lens *g*. The object (not shown) is arranged just below the objective lens *f*.

This arrangement of different pump connecting pipes at the important image points of the electron microscope renders it possible to provide the desired pressure of about 10^{-3} millimeters of mercury in the discharge tube in the vicinity of the cathode *b* and to provide substantially lower pressures of about 10^{-4} millimeters of mercury in the lower space of the electron microscope.

In the constructional form shown in the drawing, the pipes *e²* and *e³* are connected to a common pumping plant (not shown). A housing *h* is interposed between the electron microscope and the pumping plant for intercepting and equalizing the pressure variations as for instance gas outbreaks or escapes or the like. The housing *h* may be of great importance if the hollow space in the electron microscope is small and the apparatus is formed of metal.

While the invention has been described with reference to particular structural details it is apparent that modifications may be made therein. Such changes may be made without departing from the spirit and scope of the invention as set forth in the appended claims.

I claim:

1. In an electron microscope, a sealed tube, a cathode within said tube, an apertured anode within said tube, a diaphragm having a throttling opening therein spaced from said anode, a pipe extending from said tube intermediate the diaphragm and the anode for adjusting the pressure within the tube adjacent the cathode, objective and projecting lens means associated with the tube, and pipes communicating with the tube adjacent the lens means for adjusting the pressure in the tube adjacent an object to be analyzed.

2. In an electron microscope, a sealed tube, a cathode within said tube, an apertured anode within said tube, a diaphragm having a throttling opening therein spaced from said anode, a pipe extending from said tube intermediate the diaphragm and the anode for adjusting the pressure within the tube adjacent the cathode, objective and projecting lens means associated with the tube, conduits extending from said tube adjacent the lens means, a pressure equalizing housing connected to said conduits, and a pipe extending from said housing for adjusting the pressure therein.

3. In an electron microscope, a sealed tube, a cold cathode within an end of said tube, an apertured anode within said tube, a neutral diaphragm

substantially closing said end of the sealed tube and spaced from the anode, said diaphragm having a throttling opening therein, a pipe extended from said tube intermediate the diaphragm and the anode for adjusting the pressure within the tube adjacent the cathode, objective and projecting lens means associating with said tube and spaced therealong for arranging an object to be examined therebetween, and pipes communicating with the sealed tube adjacent the lens means for adjusting the pressure within the tube adjacent the object to be analyzed to a value different from the pressure adjacent the cathode.

4. In an electron microscope, a sealed tube, a cold cathode within an end of said tube, an apertured anode within said tube, a neutral diaphragm substantially closing said end of the sealed tube and spaced from the anode, said diaphragm having a throttling opening therein, a pipe extended from said tube intermediate the diaphragm and the anode for adjusting the pressure within the tube adjacent the cathode, objective and projecting lens means associating with said tube and spaced therealong for arranging an object to be examined therebetween, and conduits extending from said tube adjacent the lens means, a pressure equalizing housing connected to said conduits, and a pipe extending from said housing for adjusting the pressure within the tube adjacent the lens means to a value different from the pressure within the tube adjacent the cathode.

FRIEDRICH KRAUSE.
